UNITED STATES PATENT OFFICE.

RICHARD E. BELL, OF ST. LOUIS, MISSOURI.

TIE PLATE.

Application filed November 17, 1928. Serial No. 320,120.

My invention relates to tie plates and more particularly to tie plates of the so-called compression type, or, that is, of the type such as illustrated and described in 5 United States Letters Patent No. 1,219,224 issued to Edwin H. Bell on March 13, 1927 and No. 1,497,867 issued to William S. Boyce on June 17, 1924.

Tie plates of the compression type here- 10 tofore have been characterized by having the median portion underneath the rail recessed and then having arranged in this recessed portion a plurality of grooves, preferably arcuate in cross section, arranged so 15 that the walls thereof form a plurality of tie engaging ribs extending longitudinally of the plate. When such a plate is put in use these longitudinally extending ribs initially enter between the fibres of the tie 20 and as the lower surface of the plate becomes embedded in the tie the ribs compress the fibres into the compression grooves. Usually, the end portions of such a plate 25 were also recessed thereby creating a tie plate having two features of structure which were sometimes objectionable because, namely, first the end portions of the plate were weakened and, second, the end portions of the plate could not contact with the tie 30 until the longitudinally extending ribs formed by the walls of the compression grooves had been embedded in the tie by the weight of passing trains and, therefore, all of the weight of the rails and loads 35 passing thereover was carried by the median portion of the plate until the longitudinally extending ribs had been completely embedded in the tie.

The objects of this invention are to re- 40 move these deficiencies of structure by providing a tie plate of the compression type of strong and rugged construction and in the use of which the load carried by the plate will be evenly distributed from end 45 to end.

With these and other objects in mind one embodiment of my invention is fully shown in the accompanying drawings wherein similar characters are used to designate similar 50 parts; Fig. 1 shows the bottom of the tie plate of this embodiment of my invention; Fig. 2 is a sectional view along the line 2-2 in Fig. 1; and Fig. 3 is an end view 55 of the tie plate.

Referring to the figures, the tie plate shown in the drawings as embodying my

invention has the top thereof formed with a flat rail bearing surface 1 and a transversely extending shoulder 2 against which an edge of the rail flange abuts. The bottom of the tie plate has a pair of transversely extending spaced apart members 3 arranged to initially seat on the tie. Each of the members 3 has a short rib 4 depending therefrom, and arranged to be forced 60 into the tie sufficiently to hold the plate in position while the rail is being laid and spiked to the tie. The bottom of the tie plate has a median recessed portion between the transversely extending members 3 and 65 end recessed portions at each end of the plate beyond said members 3, all as shown in the figures. In the recessed portions 5 and 6 are formed a plurality of compression grooves 7, preferably arcuate in cross sec- 75 tion as shown, and the grooves 7 are ar- ranged so that the walls thereof meet, as shown in the figures, or are otherwise ar- ranged to form a plurality of longitudinally 80 extending tie engaging ribs 8. Preferably, the lower edges of the tie engaging ribs 8 are in a plane coincident with the tie bear- ing surface of the transversely extending members 3. The plate may be provided 85 with the usual spike holes 9.

The use and action of the tie plate shown and described is as follows: When the track is being laid the tie plate is positioned on the tie and the short transverse ribs 4 are forced into the tie sufficiently to hold the 90 plate in position while the rail is being laid and the spikes are being driven. The lower surface of the transversely extending mem- 95 bers 3 initially seat on the tie, but as trains pass over the rail seated on the tie plate these initial bearing surfaces are forced into the tie and the longitudinally extending ribs 8 enter between the fibres of the tie, as de- 100 scribed above, and as the members 3 become more firmly embedded in the tie the fibres of the tie are compressed in the grooves 7.

It will be noted that if the tie plate is formed as shown in the drawings the longitudinally extending ribs 8 in the end re- 105cessed portions of the tie plate engage the tie at the same time as the ribs 8 in the median recessed portion 5 and, therefore, during the time that the tie plate is be- 110coming embedded in the tie the load is even- ly distributed throughout the length of the plate.

In the drawings I have shown only one

embodiment of my invention although it may be readily understood that the size, shape and general arrangement of the parts comprising the tie plate may be changed within wide limits without deviating from the spirit of my invention as included in the claims set forth below.

What I claim as new and desire to secure by Letters Patent, is:—

- 10 1. A tie plate having on its bottom intermediate its ends a pair of transversely extending members, said bottom having recessed portions between said members and at each end of said plate therebeyond, and a plurality of compression grooves extending longitudinally of said plate in each of said recessed portions.
- 20 2. A tie plate having on its bottom intermediate its ends a pair of transversely extending members arranged to initially seat on the tie, said bottom having recessed portions between said members and at each end of said plate therebeyond, a plurality of arcuate shaped compression grooves extending longitudinally of said plate in each of said recessed portions, and said grooves being positioned and arranged so that the walls thereof will form a plurality of tie engaging ribs.
- 25 3. A tie plate having on its bottom intermediate its ends a pair of transversely extending members arranged to initially seat

on the tie, said bottom having recessed portions between said members and at each end of said plate therebeyond, a plurality of 35 arcuate shaped compression grooves extending longitudinally of said plate in each of said recessed portions, and said arcuate shaped grooves being positioned and arranged so that the walls thereof meet to 40 form a plurality of tie engaging ribs with the lower edges of said ribs being in the same plane.

4. A tie plate having on its bottom intermediate its ends a pair of transversely 45 extending members arranged to initially seat on the tie, said bottom having recessed portions between said members and at each end of said plate therebeyond, a plurality of 50 arcuate shaped compression grooves extending longitudinally of said plate in each of said recessed portions, and said arcuate shaped grooves being positioned and arranged so that the walls thereof will form a plurality of tie engaging ribs the lower 55 edges of which are in a plane coincident with the plane of the lower surface of said transversely extending members, and each of said transversely extending members having a short transversely extending rib depending 60 therefrom.

In witness whereof I have signed my name to this specification.

RICHARD E. BELL.
